UNITED STATES PATENT OFFICE

JOHN CHRISTIANSEN, OF RIDGEWOOD, NEW JERSEY, ASSIGNOR TO AMERICAN CAR AND FOUNDRY COMPANY, OF NEW YORK, N. Y., A CORPORATION OF NEW JERSEY

ARTICULATED CAR

Application filed January 12, 1931. Serial No. 508,060.

This invention relates to articulated cars and has particular reference to means for supporting a foot plate and vestibule unit between the adjacent end portions of two car bodies.

The present invention contemplates the association with and supporting of a foot plate between the adjacent end portions of two car bodies which are articulated by means of a construction quite similar to that shown in patent to A. E. Ostrander, et al., No. 1,727,667 of September 10, 1929.

The present invention contemplates the support of a foot plate which bridges the space between the adjacent end portions of two car bodies, primarily by a truck arranged beneath the adjacent end portions of the car bodies.

Another object of this invention is the provision of an articulated car comprising a plurality of car bodies having a combined vestibule and foot plate construction supported by a truck beneath the adjacent end portions of the car bodies; said construction being retained stationary with respect to the truck whereby the bodies swivel horizontally relative thereto.

A further object of this invention is the provision of a combined foot plate and vestibule unit interposed between the adjacent end portions of two car bodies and supported primarily by part of a single truck arranged beneath said adjacent portions, the combined foot plate and vestibule unit lapping the adjacent end portions of the car bodies and receiving a portion of its support therefrom, the construction being such that the combined foot plate and vestibule unit is retained stationary with respect to the truck, but is supported in such a manner that swiveling of the bodies in a horizontal plane relative to said unit may take place.

Other objects of this invention will be apparent from the following description taken in conjunction with the accompanying drawing in which,

Figure 1 is a top plan view showing parts of the adjacent end portions of two car bodies, articulated together, certain parts thereof being broken away,

Fig. 2 is a vertical sectional view through the parts shown in Fig. 1,

Fig. 3 is a detailed sectional view showing the resilient means for supporting the foot plate,

Fig. 4 is a sectional view on the line 4—4, Fig. 1,

Fig. 5 is a top plan view of the roller bearing member for supporting foot plate.

Referring now more particularly to the drawing, the adjacent end portions of two car bodies are shown more or less diagrammatically in Fig. 1, and are indicated at A and B, respectively. The adjacent end portions of the bodies are supported for relative horizontal swiveling movements by a single truck of any desired construction, having a bolster indicated generally at C and which, in the present instance is shown as comprising a pair of similar but oppositely disposed sections 2. The bolster construction shown in the drawing is substantially identical with that shown in the before mentioned patent to Ostrander, et al., but it is to be understood that this is merely by way of example as obviously other forms of bolsters may be employed if desired. The bolster sections are substantially channel-shaped in cross section at their centers and their webs are arranged substantially together and are each provided with longitudinal recesses 4 which, when the bolster sections are assembled as shown in Fig. 2, define a substantially cylindrical opening. Substantially midway between the ends of the bolster sections the upper surfaces thereof are arcuate in shape as at 8, and the arcuate sections support a truck center plate 10 having depending flanges 12, which engage with flanges 14 depending from the arcuate portions 8. It will be obvious that in a bolster formed of a single piece of material the upper surface thereof, midway between the ends, would be provided with a substantially circular portion and that the bolster could be provided with a longitudinal opening which would correspond in all respects to the opening defined by the mating depressions 4 of the bolster shown in the drawing.

The center plate 10 is provided with an 100

upwardly extending inner guide flange 15, circular in shape and surrounding an opening 16 formed in the center plate and arranged concentrically with respect thereto.

5 The center plate is further provided with a marginal flange 18 as clearly shown in Fig. 2.

The truck center plate 10 receives a body center casting 20 formed as a part of an inner casting 22 arranged in and secured to a retainer casting 24 secured to the center sills 26 of car body A. For connecting the casting 22 to the retainer casting 24 a pin 28 is employed. It will be apparent that the combined castings 22 and 24 define a body center casting.

As shown clearly in Fig. 2 the bearing surface of the center bearing 20 is dished or concaved as at 29 and is provided with a central aperture 30 through which the guide flange 14 projects; said flange 14 serving to restrain the center bearing 20 against excessive horizontal shifting in the truck center plate.

The center bearing 20 supports a filler block 32 having a lower bearing surface 34 which is complementary to the concaved bearing surface of the center bearing, and said bearing block is preferably hollow and provided with an internal circular flange 36 formed around an opening in the filler block, which flange is arranged around the guide flange 14 for an obvious purpose. The bearing block is formed with a convex or upper bearing surface 38 and supports a center bearing 40 formed at one end of an inner center casting 42 secured to the retainer casting 24 of car body B by means of a pin 28.

The center bearing 40 includes a concaved bearing surface 44 which conforms to the convexity of the head 38 of the filler block, and an internal apertured web 46. The openings in the center bearings and filler block align with the opening in the truck center plate and bolster and receive a king pin 48 having a head 51 resting upon the web 46 to be supported thereby. The upper end of the pin 48 is of sizable dimensions to serve as a buffing element for transmitting buffing shocks from one car body to the other. The king pin 48 is retained against vertical displacement by means of a key 49, and it will be apparent that due to the connection of the pin with the bolster by means of the key, the two center bearings and filler block are retained in assembled relation.

The center bearing 40 includes a head 50 which is rounded and is provided with a central aperture, the purpose of which will be hereinafter described.

60 The invention includes the supporting of a foot plate so as to permit passage from one car body to the other. In the present instance the articulated joint is adapted to support both the foot plate and a vestibule member; said foot plate and vestibule member be-

ing connected to form a unit, and as clearly shown in Fig. 2, the foot plate 52 which is circular, as shown in Fig. 1, has a supporting element 54 secured to its under surface at substantially the center of the plate; the member 54 being annular and having a concaved bearing surface conforming to the contour of the head 50 and supported by the latter. The element 54 constitutes a bearing member and is provided with an internal annular shoulder 56 which supports a retainer pin 58 extending through the head 50 and covering the handle portion 59 of the pin 48 and serving to retain the foot plate 52 in position on the head 50. To permit insertion or removal of the pin 48, the foot plate 52 is provided with a substantially central removable section 60.

The foot plate, it will be obvious, is supported primarily by the truck bolster and specifically by head 50 of the center bearing 40. In addition to the support just described it has been found desirable to support the foot plate 52 at its marginal edge in such a manner as to permit horizontal swiveling of the adjacent end portions of the bodies relative thereto and to that end an angle 62 is secured to the under surface of the foot plate 52 adjacent the marginal edge of the latter. As clearly shown in Fig. 4, the angle is so arranged that one leg thereof is vertically arranged to constitute a track 64 which is adapted to rest upon rollers 66 supported in bearings 68, which latter are resiliently mounted by springs 70 arranged in spring retainers 72 formed as parts of roller bearing supports 74. As shown clearly in Fig. 1, the foot plate is supported at spaced intervals by the rollers, and the roller bearing supports are secured to the adjacent end portions of the car bodies on each side of the center sills. It will be apparent that while the foot plate is rigidly supported at its center, the car bodies are free to shift relative to the foot plate in accordance with variations in track structure because of the resiliently mounted rollers or roller bearings 66. In order to prevent rotation of the foot plate 52 relative to the adjacent car bodies, any suitable or desired means may be provided. From the construction just described, it will be apparent that the bodies may swivel horizontally independently of each other and such swiveling will be relative to the foot plate.

The end walls of the bodies are provided with curved surfaces 76 which extend inwardly toward openings in the end portions of the bodies; the curved portions 76 extending approximately to the doorways formed in the ends of the bodies, and said curved portions are provided at their free ends with flanges 77 which may define parts of the door frames if desired. The curved portions 76, in effect, define longitudinal recesses in the end walls

of the car bodies, and serve to retain the vestibule unit indicated generally at 78.

The vestibule unit comprises a substantially U-shaped member having side walls 80 and 5 a top (not shown), and the side walls 78 are curved to correspond to the curvature of the portions 76 of the body end walls. The side walls 80 terminate at convenient points to leave openings or doorways through which 10 passengers may go from one body to the other. The side walls of the vestibule unit 78 have their side edges offset as at 82 to define a space between the offset portions and the curved portions 76 of the end walls to retain suitable 15 weather stripping 84. To stiffen the side edges of the side walls of the vestibule unit, the side edges, at the offset portions, are folded upon themselves as clearly shown in Fig. 1.

20 The vestibule unit is carried by the foot plate, and as shown in Fig. 4, angles 86 are employed which are connected to the vestibule unit and foot plate in any suitable or desired manner. Being secured to the foot 25 plate the vestibule unit is fixed relative thereto and the bodies A and B swivel relative to the unit, the latter having its side walls lapping the curved portions 76 of the ends of the bodies to an extent sufficient to maintain 30 the parts in proper assembled relation and to permit free swiveling of the bodies relative to the vestibule unit without obstructing the doorways formed in the ends of the car bodies.

From the above description it is believed 35 that it will be apparent to those skilled in the art that a unitary construction has been provided which includes a vestibule unit and a foot plate, the construction being primarily supported by the truck bolster and being 40 maintained fixed relative thereto. It is also believed apparent that the construction described permits swiveling of the bodies independently of each other and relative to the combined foot plate and vestibule construction. It is also obvious that the bodies are 45 free to move to conform to inequalities in track grades though preserving the original and desired relative positions of the combined foot plate and vestibule unit and the 50 car bodies.

The drawing illustrates one embodiment of the invention, but it is to be understood that they are for illustrative purposes only and various changes in the form and proportions 55 of the construction shown may be made within the scope of the appended claims without departing from the spirit of the invention.

What is claimed is:

1. In a car construction, a truck center 60 bearing, a body center bearing mounted in the truck center bearing, a filler block in said body center bearing, a second body center bearing supported by the filler block, and a foot plate mounted on and supported by the 65 second body center bearing.

2. In a car construction, a truck center bearing, a body center bearing mounted in the truck center bearing, a filler block in said body center bearing, a second body center bearing supported by the filler block, and a combined foot plate and vestibule unit mounted on and supported by the second body center bearing. 70

3. In a car construction, a truck center bearing, a body center bearing mounted in the truck center bearing, a second body center bearing arranged above the first named body center bearing and aligned with the truck center bearing, a vestibule unit, and a foot plate by which the vestibule unit is supported, said foot plate being loosely mounted on the second body center bearing. 75 80

4. In a car construction, a truck center bearing, a body center bearing mounted in the truck center bearing, a second body center bearing arranged above the first named body center bearing and vertically aligned with said first-named body center bearing and with said truck center bearing, and a foot plate and vestibule unit supported by the second body center bearing, the foot plate being loosely mounted on the said second body center bearing whereby the latter may swivel in all directions relative to the foot plate. 85 90 95

5. In a car construction, a pair of car bodies each having an underframe provided with spaced longitudinal sills, retainer castings secured to the sills, inner castings mounted in the retainer castings and having center bearings, one thereof having a head portion, and a foot plate loosely mounted on the head portion and lapping the adjacent end portions of the bodies. 100

6. In a car construction, a pair of car bodies each having an underframe provided with spaced longitudinal sills, retainer castings secured to the sills, inner castings telescopically arranged in the retainer castings and having center bearings, one thereof having a head portion, a foot plate loosely mounted on the head portion whereby the adjacent body may swivel relative thereto, said foot plate lapping the adjacent end portions of the bodies, and means connecting the foot plate to the head portion to prevent displacement of the foot plate. 105 110 115

7. In an articulated car comprising a plurality of car bodies, vertically aligned and connected body and truck center bearings for supporting the adjacent end portions of the bodies, and a combined foot plate and vestibule unit supported by said center bearings. 120

8. In an articulated car comprising a plurality of car bodies, vertically aligned and connected body and truck center bearings, a foot plate supported by the bearings and lapping the adjacent end portions of said bodies, and bearing elements carried by the bodies on which said foot plate rests. 125 130

9. In an articulated car comprising a plurality of car bodies, a vestibule unit fitted into the adjacent end portions of said bodies, vertically aligned and connected body and truck center bearings for supporting the adjacent end portions of the bodies, and a foot plate supported by one of the body bearings and to which the vestibule unit is secured. 70
10. In an articulated car, a plurality of car bodies, a foot plate bridging the space between the adjacent end portions of said bodies, a track member depending from the foot plate, and resiliently mounted roller bearing elements on the adjacent end portions 75 of the bodies for cooperation with said track member to support the foot plate.
11. In an articulated car comprising a plurality of car bodies, means for supporting a foot plate between the adjacent end portions 80 of the bodies comprising a body center bearing secured to the end portion of one of the bodies and provided with a head, a bearing member secured to the foot plate adapted to seat on said head, and means extending through the bearing member and into the head to prevent relative sidewise shifting of the foot plate and center bearing. 85
12. In an articulated car, a pair of car bodies having their adjacent end walls inwardly recessed, a vestibule unit arranged between the adjacent car bodies and fitted into said recesses whereby the bodies may 90 swivel relative thereto, a foot plate to which said vestibule unit is secured, said foot plate lapping the adjacent end portions of said bodies and being provided with a depending track member, and a plurality of resiliently mounted roller bearing elements on the adjacent end portions of the bodies with which the track member engages to support the foot plate, said bearings being horizontally shiftable relative to the foot plate upon shifting of the bodies and being each individually rotatable during such shifting movement. 95
13. In an articulated car, a pair of car bodies having their adjacent end walls inwardly recessed, a vestibule unit arranged between the adjacent car bodies and fitted into said recesses whereby the bodies may 100 swivel relative thereto, vertically aligned body and truck center bearings for supporting the adjacent end portions of the bodies, a foot plate to which said vestibule unit is secured and by which said unit is supported, said foot plate lapping the adjacent end portions of said bodies and being resiliently supported thereby. 105
14. In an articulated car, a pair of car bodies having their adjacent end walls inwardly recessed, a vestibule unit arranged between the adjacent car bodies and fitted into said recesses whereby the bodies may 110 swivel relative thereto vertically aligned and connected body and truck center bearings for supporting the adjacent end portions of the bodies with which the track member engages. 115
15. In an articulated car, a pair of car bodies, a combined vestibule unit and foot plate between the adjacent end portions of said bodies and means for supporting said combined vestibule unit and foot plate comprising a body center bearing for one of the bodies on which the foot plate is supported, said bearing being capable of swiveling in substantially all directions with the car body and relative to the foot plate, and resiliently mounted bearing elements on the adjacent end portions of said bodies on which the foot plate rests. 120
16. In an articulated car comprising a pair of car bodies, means for permitting passage from one body to the other comprising a vestibule unit, a foot plate to which the unit is secured, and a stiffening angle secured to the foot plate adjacent its marginal edge and having one leg thereof vertically arranged to define a track member. 125
17. In an articulated car comprising a pair of car bodies, means for permitting passage from one body to the other comprising a substantially U-shaped vestibule unit, a foot plate lapping the adjacent end portions of said bodies and to which the vestibule unit is secured whereby said unit is supported, a track member depending from the foot plate adjacent its marginal edge, and a bearing member secured to the under surface of the foot plate at substantially the center thereof. 130
18. In an articulated car, a pair of car bodies, a vestibule unit arranged between and fitted into the adjacent end walls of said bodies, vertically aligned and connected body and truck center bearings for supporting the adjacent end portions of the bodies, a foot plate arranged between the adjacent end portions of the bodies, means connecting the foot plate and vestibule unit whereby swiveling movement of the bodies is relative to said foot plate, and a bearing element on the foot plate engaging one of the body center bearings for supporting the foot plate at substantially its center. 135
19. In an articulated car, a pair of car bodies having their adjacent end walls recessed, a vestibule unit arranged between the bodies and fitted into the recesses in the end walls, a foot plate secured to the vestibule unit and extending over the adjacent end portions of the said bodies, a track member secured to the foot plate, and individually rotatable bearing elements resiliently mounted on the adjacent end portions of the bodies with which the track member engages. 140

20. In an articulated car, a pair of car bodies having the adjacent end walls recessed, a vestibule unit arranged between the bodies and fitted into the recesses in the end
5 walls, a foot plate secured to the vestibule unit and extending over the adjacent end portions of the said bodies, a stiffening angle secured to the foot plate and having one leg thereof depending vertically from said foot
10 plate to define a track member, and resiliently mounted bearing elements on the adjacent end portions of the bodies with which the track member engages.

21. In an articulated car, a pair of car bodies, body and truck center bearings for supporting the adjacent end portions of said bodies, one of said body center bearings being provided with a convexed head, a foot plate bridging the space between the end portions
15 of said bodies, roller bearing means on the adjacent end portions of the bodies for supporting the foot plate adjacent its marginal edge, a bearing element secured to the foot plate and provided with a concaved bearing
20 surface resting on the convexed head of the body bearing for supporting the foot plate at substantially the center of swiveling movement of the bodies, and means for retaining the foot plate in position on the supporting head.

22. In a car construction, a truck center bearing, a body center bearing mounted in the truck center bearing, a filler block mounted in said body center bearing, a second body
25 center bearing mounted on the filler block and having an internal web and a convexed head portion, said convexed head portion defining a support adapted to position a foot plate, and a king pin securing said center
30 bearings and filler block together, said king pin being supported by the web.

In witness whereof I have hereunto set my hand.

JOHN CHRISTIANSEN.
